UNITED STATES PATENT OFFICE

RAPHAEL JACOBUCCI, OF CLEVELAND, OHIO

PRINTING PRESS

Application filed January 22, 1927. Serial No. 162,918.

This invention relates to printing presses, and has for one of its objects to provide a device of this character capable of simultaneously printing upon opposite sides of the paper in ordinary ink, and likewise imparting impressions upon the printed body in one or more colors, and in one operation.

Another object of the invention is to provide a device of this character capable of simultaneously printing upon opposite sides of the paper, drying the ink by artificial heat, and imparting one or more colors to the printed body and in a continuous operation.

Another object of the invention is to provide a device of this character in which provision is made for intermittently moving a strip of paper forwardly, simultaneously printing upon opposite sides of the strip as it is moved, imparting one or more colors to the printed surfaces, and severing the printed and colored strip at predetermined intervals.

Another object of the invention is to provide a device of this character which will print on both sides of the paper, apply one or more colors to the printed surfaces, apply artificial heat to the printed body, and sever the same at predetermined intervals.

Another object of the invention is to provide a device of this character which is simple in construction, self contained and operative from a single drive shaft, and wherein provision is made for adjusting the parts to control the correlative action.

With these and other objects in view, the invention consists in certain novel features of construction as hereafter shown and described, and in the drawings illustrative of the preferred embodiment of the invention:

Figure 1 is a plan view, without the inking rollers.

Figure 2 is an end elevation, partly in section.

Figure 3 is a side elevation.

Figure 4 is a transverse section on the line 4—4 of Figure 2, without the inking disks.

Figure 5 is an enlarged detail of the feeding mechanism for the color applying strips.

Figure 6 is a plan view of the parts shown 50 in Figure 5.

Figure 7 is an enlarged detail of one of the color strip feeding trips.

Figures 8, 9 and 10 are enlarged details of the crank of the printing plate operating mechanism.

Like reference characters are employed to designate like parts in all the figures of the drawings.

The improved device includes a supporting frame of suitable construction and represented as a whole at 10, and provided with spaced vertical supports 11 at the ends and a plurality of similar vertical supports 12 intermediate the ends. At their upper ends the members 11 are formed with upwardly opening sockets or bearings 13, in spaced relation, while the intermediate supports are provided with like sockets 14. The sockets 13 and 14 are designed to receive the terminals of shafts 15, each shaft carrying roll of color transfer paper indicated at 16. Supported from the members 11 and 12 are bearing rollers 17, one coaxing with each of the rolls 16, as shown.

Depending from the frame 10 are hangers, one of which is represented at 18, and mounted for rotation in the hangers are spaced shafts 19, the shafts carrying serrated drums 20 in coaxing pairs, one pair for each of the strips 21 of color transfer paper leading downward respectively from the rolls 15 and between the drums, the drums being loose upon the shafts 19.

Mounted upon one of the shafts 19, and rotative therewith, is a ratchet 22, and the drum 20 nearest the ratchet is provided with a pawl 23 engaging the teeth of the ratchet.

Rotative on the shaft 19 which carries the ratchet 22 is a sleeve or collar 24, the collar having a set screw 25 enabling it to be coupled in adjusted position to its shaft. Extending from the collar 24 is a hood or guard 26 which projects over a part of the ratchet and holds the pawl away from the ratchet teeth, the object to be hereafter described.

The main drive shaft is represented at 27 and is supported in hangers, one of which is shown at 27', beneath the frame 10.

Pivoted at 30 on the frame 10 is a trip

100

arm 29, the latter coupled by a rod 29' to the drum 20 which carries the ratchet 22.

One of the end drums 20 is provided with a recess 20' and a disk 20'' is housed in said recess and is loosely mounted upon the shaft 19. The drums 20 upon the same shaft are mounted upon a sleeve 19' and the sleeve 19' is loose upon the shaft 19. The shaft 19 is fixed to the frame of the press. The guard 26 is adjustably fixed to the shaft 19. The pawl 23 is pivoted upon the disk 20'' and the rod 29' is pivoted at its lower end to the disk 20''.

Mounted for rotation in the standards 11 and 12 and above the shaft 27, is a counter shaft 31 operative from the shaft 27 by gears 32 and 33, and having a cam member 34, in position to intermittently actuate the trip member 29 once at each revolution of the shafts 27 and 31.

By this arrangement when the shaft 27 is rotated, the shaft 31 will be correspondingly rotated and cause the cam 34 to depress the arm 29 and cause the rod 29' to move the drums 20 a portion of a revolution, and cause the pawl 23 to correspondingly actuate the drums 20 for a short distance, the object to be hereafter explained. By adjusting the hoods 26 the action of the pawls 23 can be controlled 30 to correspondingly control the distance which the drums are rotated.

Supported upon the frame 10 at one end is a bracket 35 carrying a platform 36 and a vertical stud 37 to receive a roll 38 of the paper to be printed.

Extending from the frame 10 at one end is a bracket 39 having a longitudinal slot 40, while a similar bracket 41 extends from the opposite end of the frame and is provided with a longitudinal slot 42.

Slidable in the slot 40 is a stud 43 including a platform 44 rotatively supporting a small hollow drum 45, and slidably supported in the slot 42 is a like stud 46 including a platform 47 and rotatively supporting a hollow drum 48.

Depending from the bracket 39 is a threaded lug 49 in which a threaded rod 50 operates, and swivelled at its inner end in the lug 43, while a similar threaded lug 51 depends from the bracket 41 and carries a threaded rod 52 swivelled at its inner end in the lug 46.

By this means it will be obvious that the drums 45 and 48 may be adjusted longitudinally of the brackets 39 and 41 by actuating the threaded rods 51 and 52.

The drums 45 and 48 are provided with heating means, for instance gas burners or the like, as indicated conventionally at 54 and 55, to rapidly dry the ink upon the strip 56.

Extending between the members 11 are spaced plates 57 and 58, which form the platen elements of the improved press, and 65 will be clothed with the usual tympan mem-

bers, not shown, the members 57 and 58 being coupled at suitable intervals by web like stays 59.

In preparing the improved press for operation, the paper 56 is first passed over the surface of the platen member 57 and around the drum 48, thence between the platen members 57 and 58, thence around the drum 45, thence over the platen member 58, thence between pull rollers 60 and 61, the latter provided with means for being intermittently rotated to draw the paper outwardly after being printed and into the severing devices indicated conventionally at 62.

The frame 10 includes transversely arranged spaced guide members 63 having guide channels 64, preferably V shaped, in their upper faces, as shown in Figure 3. Slidably disposed above each of the guides 63 is a supporting member 65, each of the latter having a rib 66 engaging in one of the guide channels 64.

Rising from each of the members 65 is a bracket 67, the brackets supporting type holding frames 68, the latter indicated conventionally at 69, and adapted to be adjusted by set screws 70.

The members 65, 67 and 68 are movable toward and away from each other to cause the printing elements 69 to be compressed against the paper 56 as the latter is moved over the tympan elements.

Depending from each of the members 65 is a hanger 71, the hangers at each side of the shaft 25 being coupled respectively by counter shafts 27.

The main drive shaft 27 is provided with spaced double cranks 73, the cranks being coupled to the shafts 72 by rods 74, as shown.

By this means when the shaft 27 is rotated, the type carrying elements will be simultaneously moved toward and away from each other, to produce the printing action.

The ink applying devices are indicated conventionally at 79, but form no part of the present invention and require no further description.

The operation is simple and may be summarized as follows:

The paper 56 to be printed is threaded around the drums 45 and 48 as before described, and the color transfer paper 21 passed downward over the guide rollers 17 and between the pull drums 20. Then when motion is imparted to the shaft 27, the type elements 68-69 are simultaneously moved toward each other and the printing operation completed including the transference of the coloring matter from the strips 21. The coacting parts 29-29' and 34 are so adjusted that when the shaft 27 operates the printing action, the rollers 20 will be rotated to a sufficient extent to move the requisite portion of the colored transfer element into position opposite the type bearing elements, so that as

the latter are intermittently operated by the action of the cranks 73 and links 74, the colored transfer elements 21 will be likewise intermittently actuated through the medium of the cam 34 and arm 29. Both sides of the paper are printed by one operation, one side being printed while the paper is passing over the platen member 57, and the other side printed while the paper is passing over the platen member 58, and the ink dried by the action of the burners 54—55.

The paper elements 21 are of transfer material capable of imparting its coloring substance to the paper 56, when it is printed and are used but once, the used portions being torn off or otherwise disposed of after passing between the drums 20.

The throw of the drums 20 are the same at each rotation of the shaft 27, but by adjusting the hoods 26, the pawl 23 may be engaged with any required number of the teeth of the ratchet at each stroke, to control the amount of the transfer material used. Thus waste of the transfer material is avoided.

Having thus described the invention, what is claimed as new is:—

1. A printing press comprising a supporting frame, platen members supported on said frame in spaced relation, a printing form bearing member coacting with each of said platen members, means for simultaneously and intermittently moving said printing form bearing members toward and away from said platen members, means for intermittently moving a printing sheet over said platen members, a sheet of color imparting material, a drum operative to feed said color imparting material over said printing sheet, a ratchet coacting with said drum, a pawl device engageable with said ratchet, means for intermittently actuating said drum, and a guard element operative to hold said pawl away from said ratchet, and means for adjusting said guard element to control the throw of said drum.

2. A printing press comprising a supporting frame, platen members supported on said frame in spaced relation, a printing form bearing member coacting with each of said platen members, means for simultaneously and intermittently moving said printing form bearing members toward and away from said platen members, means for intermittently moving a printing sheet over said platen members, standards rising from said frame, shafts supported for rotation by said standards, a feeding drum and ratchet rotative with said shaft, a sheet of color imparting material engageable with said drum and movable thereby over the printing sheet, a pawl device rotative relative to said shaft and engageable with said ratchet, a guard element operative to hold said pawl away from said ratchet, and means for adjusting said guard element to control the throw of said drum.

3. In a platen printing press a pair of vertically disposed platens spaced apart and back to back, and horizontally moving form carriers operable there-against, said carriers simultaneously moving toward and away from one another, means for causing said simultaneous operation, and means whereby a vertically disposed strip of paper moves horizontally over the faces of both of said platens, and between said platens.

4. As claim 3 and drying elements over which said paper passes.

5. As claim 3 and drying elements over which said paper passes, said elements consisting of heated drums.

6. As claim 3 and drying elements over which said paper passes, said elements consisting of heated drums, located at each end of said platens.

7. As claim 3 and drying elements over which said paper passes, said elements consisting of heated drums, located at each end of said platens, and means for intermittently moving the paper over the platens.

8. In a platen printing press a pair of vertically disposed platens spaced apart and back to back, and horizontally moving form carriers operable there-against, and means whereby a vertically disposed strip of paper moves horizontally over the faces of both of said platens.

9. In a platen printing press a pair of vertically disposed platens spaced apart and back to back, and horizontally moving form carriers operable there-against, and means whereby a vertically disposed strip of paper moves horizontally over the faces of both of said platens, and means for moving transfer ribbons over said paper.

10. As claim 9 and between said paper and said forms.

11. As claim 9 and between said paper and said forms, the movement of said ribbons being vertical.

12. As claim 9 and between said paper and said forms, the movement of said ribbons being vertical, and means for intermittent movement of said ribbons.

13. In a platen printing press, a pair of vertically disposed platens spaced apart and back to back, and horizontally moving form carriers operable thereagainst, said carriers simultaneously moving toward and away from one another, means for causing said simultaneous action and means whereby a vertically disposed strip of paper moves horizontally across the faces of both of said platens.

14. In a platen printing press a pair of vertically disposed platens spaced apart and back to back, and horizontally moving form carriers operable there-against, said carriers simultaneously moving toward and away from one another, means for causing said si-

multaneous operation, means whereby a vertically disposed strip of paper moves horizontally over the faces of both of said platens, and means for severing the end from said strip of paper.

5 In testimony whereof I affix my signature.

RAPHAEL JACOBUCCI.
